Primary Examiner — Ian Simmons*Assistant Examiner* — Yolanda Robinson(74) *Attorney, Agent, or Firm* — Scully, Scott, Murphy & Presser, P.C.(57) **CLAIM**

The ornamental design for an endoscope operating unit, as shown and described.

DESCRIPTION

FIG. 1 is a perspective view of an endoscope operating unit, showing a first embodiment of my new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The evenly segmented broken lines show portions of the endoscope operating unit that form no part of the claimed design.

1 Claim, 3 Drawing Sheets(56)
